PHOTOGRAPHIC RECORDING OF SOUND

Edward W. Kellogg, Moorestown, N. J., assignor
to Radio Corporation of America, a corporation
of Delaware

Application September 14, 1935, Serial No. 40,557

16 Claims. (Cl. 179—100.3)

This invention relates to the photographic recording of sound, and has for its principal object the provision of an improved apparatus and method of operation for obviating the fogging or poor delineation which tends to occur at the boundary of a small unexposed record area largely surrounded by an exposed area.

In the making of variable width photographic records over-modulation frequently occurs without such serious consequences as to render the recording useless. The maximum modulation which can be had without distortion calls for widening the transparent part of the track to the full possible track width as a maximum, and to zero width as a minimum. If the recording galvanometer executes movements larger than sufficient to attain this degree of modulation (which is usually described as "100% modulation") the tops and bottoms of the waves are cut off and distortion results. There is no way of curing this distortion.

Deflections of the galvanometer beyond the point at which the track width becomes zero, result in isolated clear areas, instead of the desired continuous strip of clear area of variable width. These isolated areas end in more or less sharp points where the boundary lines come together and intersect. If in the final record these points were infinitely sharp, the distortion would be only that which is inevitable with over-modulation, but the imperfections of the photography result in fogging in, or rounding off the sharp points, and the result is a more abrupt change in the light transmitted through the record when the scanning beam crosses this point, than would be the case with the sharp point. Under these conditions, the distortion is more objectionable, giving a peculiarly harsh sound. It is the purpose of my invention to reduce the fogging which occurs at the point where the width of the clear area falls to zero and thereby reduce the harmful effects of the over-modulation.

In certain types of recording, as will be explained, the breaking up of the sound track into a series of isolated clear areas is not confined to conditions of over-modulation, but a similar photographic effect occurs at the end of each clear area and distortion results. This distortion may be removed by the application of the principle of my invention.

The invention will be better understood from the following description when considered in connection with the accompanying drawings, and its scope will be pointed out in the appended claims.

Referring to the drawings,

Fig. 1 is a diagrammatic illustration of a recording apparatus to which the invention may be applied,

Fig. 2 illustrates the type of sound record produced by the apparatus of Fig. 1,

Fig. 3 indicates some of the various positions a triangular light beam may assume with respect to a light slit,

Fig. 4 is an enlarged detail of the record,

Fig. 5 illustrates the rounding effect produced at the tips of the small record areas by fogging,

Fig. 6 illustrates a light beam which is modified in contour to eliminate fogging and the resultant distortion,

Figs. 7, 8, and 9 illustrate the improved type of record produced by the modified light beam,

Fig. 10 illustrates the type of track produced when the base of the triangular light beam passes across the light slit,

Figs. 11 to 15 are curves illustrating the relation between input and output resulting from the use of differently spaced and differently shaped light beams,

Fig. 16 illustrates a form of light beam which avoids the type of distortion illustrated by Fig. 10, and

Figs. 17 to 22 illustrate in somewhat different form the same phenomena as Figs. 11 to 15.

The recorder of Fig. 1 includes a lamp 30 from which light passes through the aperture 31 of a mask 32 and lenses 33 and 34 to the vibratable mirror 35 of a recording galvanometer. Light reflected from the mirror 35 passes through a lens 36, the slit 37 of a screen 38 and lens 39 to the surface of a record medium 40. Lens 34 produces an optical image of aperture 31 in the plane of the screen 38. Movements of the mirror cause this optical image or light spot to move up and down, thereby illuminating varying fractions of the slit 37. The illuminated portion of slit 37 is imaged on the film by lens 39, producing a fine line of light whose length varies in accordance with the vibration of mirror 35, thereby exposing a band of film which varies in width.

Figures 2 and 4 show the appearance of a print of a record so made. It will be convenient to refer to the light spot, as a triangle, since, apart from over-modulation, a triangular shaped light spot suffices. The full width rectangular portion at the top of the triangle plays no part in normal recording, and the sharp extension of the vertex of the triangle is the subject matter of this invention.

Fig. 3 illustrates the manner in which the movements of the triangular shaped light spot 41 varies the fraction of the slit 42, which receives illumination, from a minimum length with the triangle in the highest position to full length with the triangle in the lowest position. The actual width of the slit 42 is less in proportion to the size of the triangle 41 than can be shown on a diagrammatic drawing. Therefore, the slanting intersection is not a material factor in the length of the illuminated portion of the slit which may be thought of as determined by the intersection 55

of the edge of the triangle with a single line at the center of the slit.

If, while the film is moved continuously, the galvanometer vibrates without over-modulation, the exposed area of film varies in width in such a way as to produce a perfect picture of the light spot movement as illustrated in Fig. 4. Should over-modulation occur so that the vertex of the triangle crossing the slit, the length of the line of light on the film falls to zero. This brings the exposed area of film to a sharp point every time the vertex crosses the slit, as indicated in Fig. 7, in which, as in all of the illustrations of record wave forms shown herein, an exposed area in the initial recording is shown white, although in the negative it would be black on a white background. The figures therefore illustrate prints rather than negatives. If the photographic materials employed had perfect resolution the record would show the sharp points of Fig. 7. Under these conditions the primary need of my invention would be obviated. Those who have studied photographic images however, are familiar with the fact that diffusion of the light in the emulsion results in rounding or fogging in of sharp corners. Each minute element of the surface of the film receives its exposure in part from light which, initially, strikes adjacent elements. At the very tip of a sharp pointed illuminated area, although the surface of the film may receive full exposure, the minute element of illuminated film imparts some of its light to adjacent areas, but receives no light in return, it therefore receives less exposure than an element well within the exposed area. It will be obvious that some loss of exposure of the negative due to this effect occurs at all edges of exposed areas, but the loss becomes practically twice as great when the unexposed areas are on both sides, as at an acute angle. In making a print the point of the clear area is darkened in part due to the fact that the negative at this point has had less exposure, and therefore transmits some light, and also by contribution of light from the more highly illuminated areas on both sides. Thus, both in the recording and printing there is a tendency to round off the point of the exposed area. The resulting sound track is shown in Fig. 5, which illustrates the effect of over-modulation in which the vertex of the triangle crosses the slit, but the base does not.

If over-modulation causes the base of the triangle of Fig. 3 to cross the slit, the illumination suddenly changes from full slit length to zero, and the record would appear as shown in Fig. 10. This produces much worse distortion than the rounding of the points, because the sudden change of light, in reproduction, is much greater. Such an effect however, can be entirely avoided by an adequate extension of the aperture 31, or the addition of a rectangle on the base of the triangle, as shown in Fig. 16. Crossing of the slit by the base of the triangle occurs less frequently than crossing by the vertex, for the reason that it is usual to apply a bias to the galvanometer during periods of low modulation which causes it to vibrate about a mean position close to the vertex, instead of about a mean position in which the slit is 50% illuminated. This practice of biasing is for the purpose of reducing ground noise. Although the bias is only supposed to be applied when the modulation is low and danger of over-modulation slight, the bias can not be in-

stantly changed back to zero, in case of a sudden increase in modulation. Under these conditions the high modulation occurs with the galvanometer slightly biased and there may be frequent crossings by the vertex, but none by the base of the triangle.

Since in making photographic sound records by means of an optical system of the type shown in Fig. 1, occasional crossings of the slit by the vertex of the triangle are practically inevitable, it is important that the harmful effect on sound quality be minimized, and in accordance with my invention this is accomplished by extending the vertex of the triangular aperture 31 of Fig. 1, thereby producing a light spot of the shape shown in Fig. 6. When the tip of such a light spot crosses the slit, the exposed areas of the negative have their points drawn out as shown in Fig. 8. Since the extreme vertical dimension of the light spot has been increased by the extension of the vertex, over-modulation which without this extension would result in crossings by the tip of the triangle, would in many cases not be sufficient to cause the tip of the extension to cross. Under these conditions the illuminated area never becomes zero in width, but assumes the shape illustrated in Fig. 9.

The nature of the distortion which occurs in the case of over-modulation is illustrated in Figs. 11 to 15. Galvanometer deflection is plotted horizontally and photocell light, which is the output, is plotted vertically. It is well known that for distortionless reproduction this relationship should be a straight line over the range used, as illustrated in Fig. 11. Were there no fogging of the tips of the exposed areas, crossings of the slit by the vertex of the triangle would result in a break in the input-output line, such as is shown at A in Fig. 12 with corresponding breaks in the output wave shape shown at A'. Fig. 12 also shows a break at B where the entire slit is illuminated and no further increase in light is possible. Over-modulation in both directions is shown in Fig. 12. In Figs. 13, 14, and 15, only over-modulation in the direction of zero slit illumination is shown.

Since the light cannot be modulated beyond the zero point, over-modulation inevitably involves a break in the curve. The effect of such a break however, is made worse by rounding the points as shown in Fig. 5. Fig. 13 shows at C (as compared with A in Fig. 12) the effect of the fogging on the input-output characteristic, and at C', the effect on the output wave shape.

The effect on the input-output characteristic and on wave shape, of the sharp extension of the triangular vertex (with a resulting record like Fig. 8) is shown in Fig. 14. In this figure a slight disturbance is indicated at D to show the effect of fogging which may occur at the tip of the extension. The transition from the sloping to the horizontal portion of the characteristic would inevitably be more gradual than without the extension, and a slight abrupt termination as at D, due to fogging, if not completely eliminated, would be of much smaller magnitude, as indicated by comparing Fig. 14 and Fig. 13. In fact, if the extension tapers gradually to a sharp tip, the characteristic would in general involve a smooth transition curve without any sharp breaks, as indicated at E, in Fig. 15. If the over-modulation is not sufficient to cause the tip of the extension to cross the slit, the characteristic would always be like Fig. 15.

If the output wave shapes corresponding to characteristic shown in Figs. 11 to 15 are analyzed, it will be found that for a pure tone input a characteristic such as shown in Fig. 11 will give 5 a pure tone output;—Fig. 12 will give a series of harmonics or overtones which represent distortion;—Fig. 13 would give practically the same series of overtones as Fig. 12, with the addition of a number of still higher harmonics or overtones, 10 and it is these overtones of higher frequency which give the distortion the harsher sound. The output corresponding to Fig. 14 would also have a series of overtones, but they would be of much smaller magnitude compared with the desired 15 fundamental than those of Fig. 13, especially the overtones of highest frequency. The output wave corresponding to the characteristic of Fig. 15 with its smooth transition at E, would have less harmonics than those of any of the other figures 20 (except Fig. 11) and the overtones of extra high frequency in particular would be almost completely eliminated. The effect on the reproduced sound would be to make the effects of over-modulation much less noticeable, and much less 25 irritating.

The objectionable effect of over-modulation resulting from the base of the triangle crossing the slit may also be reduced by an expedient similar to extending the vertex, namely, by rounding the 30 corners 48 of the aperture 31 of Fig. 1 where the end of the rectangle intersects with the side of the triangle. Thus, at both extremes of over-modulation a smooth transition curve, like that on Fig. 15, would be introduced between the sloping and horizontal parts of the characteristic, instead of a sharp break like that of Fig. 12. The 35 advantage of such a rounding of the corners in this case, is not because of fogging of the film. In fact, the tendency of fogging is to reduce the 40 sharpness of the break in the characteristic when the base crosses the slit.

My invention may be applied with special benefit to the recording of sound by means of a double track system which is the subject of a copending application of Glenn L. Dimmick, Serial No. 45 32,734, filed July 23, 1935 (Docket 10,403). The light beams which pass through the two tracks illuminate two photocells, the outputs of which are differentially connected. The net photocell 50 output current under these conditions is proportional to the algebraic difference between the light transmitted through the two sides of the track. With this arrangement each track might be a complete record of the waves, recorded in 55 opposite phase, so that the widest part of one track is opposite the narrowest part of the other. This would constitute a push-pull system corresponding to what is commonly described as a "Class A" push-pull system in electrical amplifiers. In the system as applied however, one 60 track is employed to register only the swings of the galvanometer in one direction from the neutral position, while the other track records only the swings in the opposite direction. The complete 65 recording of a wave therefore, calls for the cooperation of the two sides of the track. In the system covered in the aforementioned application, the two sound tracks are recorded by means of two triangular shaped apertures whose images 70 are arranged in relation to the slit as shown in Fig. 17. The galvanometer and lens arrangement is the same as shown in Fig. 1, but the mask 75 32 in Fig. 1 is replaced by one having two openings instead of one. The two light spots, 43 and 44 on Fig. 17, move up and down together. They

should be so adjusted and positioned that both vertices touch the middle line of the slit when the galvanometer mirror is in neutral position. When the galvanometer vibrates the exposed areas take the forms indicated at 45 and 46. The resulting 5 output wave is found by plotting the algebraic difference between the widths of clear areas 45 and 46, considering 45 as positive and 46 as negative. Such an output wave is plotted and shown at 47. If the aperture images are not correctly 10 placed, so that for a small range of movement neither vertex crosses the middle of the slit, there will be gaps in which there is no light transmitted through either track, and the resulting 15 wave shape will be as shown at 49 in Fig. 18. Fig. 19 shows the effect of overlapping in the triangle positions. In this case there is a small region within which some light is transmitted through both sides of the track and in plotting the resulting 20 wave, the difference between the widths of the two openings is the ordinate. Since in Fig. 19 the overlap is the result of incorrect location of the triangles, wave shape distortion results, the output wave being excessively steep at 25 the points where it crosses the zero line. 25

In the push-pull system overlap in the positions of the tips of the apertures is permissible, provided the triangles themselves are correctly 30 positioned, and the algebraic difference in the widths of the two aperture extensions when plotted against position, is a straight line. Thus, in Fig. 20 the triangles themselves are located as in Fig. 17, but the vertex extensions result in slight overlaps of the exposed areas. When the algebraic difference is plotted, an undistorted 35 wave results. In the shaping of these extensions, allowance may be made for the effect of fogging at the extreme tip, the shape being worked out experimentally to produce minimum distortion. Overlapping of the negative and positive waves, 40 and the production of an overall characteristic free from distortion, is analogous to the superposition of the characteristics of two oppositely connected vacuum tubes in what is commonly described as a "Class B" amplifier. 45

The push-pull system which I have just described has certain important advantages over the usual single track system, especially in the reduction of ground noise during periods of low modulation, but it is obvious that this system 50 involves a great many crossings of the slit by the tips of the triangular apertures, and on each such crossing wave shape distortion may occur due to fogging. The importance of vertex extensions is therefore much increased by the employment of such a push-pull system. Where the ends of the transparent areas are rounded by fogging, as shown in Fig. 5, no adjustment of triangle position can eliminate or neutralize the breaks in the resulting curve, which would have 60 the appearance indicated at 50 in Fig. 21. With the points of the clear areas drawn out, by the employment of the vertex extensions in the mask, it becomes quite easy to obtain a substantially 65 linear relation between light spot position and output.

Fig. 22 shows a form of vertex extension especially adapted to the push-pull system. The light is never entirely cut off from either track, and there is no question of a possible final sharp tip 70 where fogging could produce even a slight abrupt change in transmitted light.

In the following appended claims, the terms "triangular aperture" or "triangular light spot" 75 or equivalent terms are employed to designate 75

apertures or light spots whose form is based on a triangle, but in which an extension may have been made in either direction as herein described, and by vertex of the triangle is meant the place at which the sloping sides would intersect had not an extension been employed.

I claim:

1. The method of producing variable width photographic sound records having portions wherein the unexposed area is relatively narrow, which includes conforming a light beam to a shape adapted to prevent fogging of said narrow areas, modulating said beam in accordance with the sound to be recorded, and applying said modulated beam to said record.

2. In an apparatus for producing a photographic sound record having relatively narrow unexposed areas, the combination of means for producing a light beam so shaped as to prevent fogging of said narrow areas, means for modulating said beam in accordance with the sound to be recorded, and means for applying said modulated beam to said recorder.

3. In an apparatus for producing a photographic sound record having unexposed areas the boundaries whereof are close together, the combination of means including a mask provided with a triangularly-shaped aperture extended at its apex to prevent fogging of said areas, means for modulating said beam in accordance with the sound to be recorded, and means for applying said modulated beam to said recorder.

4. In an apparatus for producing a photographic sound record having relatively narrow unexposed areas, the combination of means including a triangularly-shaped aperture shaped at its apex to prevent fogging of said areas, means for modulating said beam in accordance with the sound to be recorded, and means for applying said modulated beam to said recorder.

5. In an apparatus for producing a photographic sound record having narrow unexposed areas, the combination of means for producing a light beam having an edge so formed as to prevent fogging of said areas, means for modulating said beam in accordance with the sound to be recorded, and means for applying said modulated beam to said recorder.

6. In the production of a variable area sound record of the photographic type, the method of minimizing distortion which includes maintaining a residual minimum of exposed area throughout the record length whereby the fogging effect otherwise produced at relatively narrow record areas is eliminated.

7. In the production of a variable area sound record of the photographic type, the method of minimizing distortion which includes retarding the rapidity with which the exposed area of said record approaches zero whereby the fogging effect otherwise produced at relatively narrow record areas is eliminated.

8. In an apparatus for producing variable width records of the photographic type, means for producing an exposure area which varies in accordance with the signal to be recorded, and means for maintaining the width of said area above a predetermined minimum whereby the fogging effect otherwise produced a relatively narrow record areas is eliminated.

9. A variable width photographic record in

which the transparent areas which correspond to the recorded waves are prolonged by narrow extensions in the direction of motion of the film, whereby wave-shape distortion due to fogging of the photographic emulsion is reduced.

10. In apparatus for making variable width photographic records a mask with an aperture having two substantially intersecting edges, and means for prevention of distortion due to fogging, comprising an extension of said aperture at 10 the point of intersection of said edges.

11. In apparatus for making variable width photographic records means for producing a non-linear relationship between input to said apparatus and the width of the exposed area of said record, whereby the rate of change of said width with respect to input, is gradually reduced as a limiting value is approached.

12. In apparatus for making variable width photographic records, means for producing a non-linear relationship between input to said apparatus and the width of the exposed area of said record, whereby the rate of change of said width with respect to input, is gradually reduced as the width of the exposed area approaches zero.

13. In a system for making variable width photographic records, a galvanometer, means establishing a relationship between the deflections of said galvanometer and the width of the exposed area of the record, said relationship being substantially linear throughout the major portion of the possible range of modulation, and non-linear near a limit of modulation, such that the limiting value of width is approached more gradually.

14. Sound recording apparatus comprising a light source, an aperture plate for defining a beam of light, a galvanometer for deflecting the beam of light in accordance with sounds to be recorded, a slit, means for focusing said beam on said slit to form an image of said aperture and means for focusing the light passing through the slit on a film, the said aperture plate being provided with opposed triangular apertures having their vertices extended with a gradually decreasing angle between their sides.

15. Sound recording apparatus comprising a light source, an aperture plate for defining a beam of light, a galvanometer for deflecting the beam of light in accordance with sounds to be recorded, a slit, means for focusing said beam on said slit to form an image of said aperture and means for focusing the light passing through the slit on a film, the said aperture plate being provided with opposed triangular apertures having their vertices extended a distance not less than the altitude of the triangle.

16. Sound recording apparatus comprising a light source, an aperture plate for defining a beam of light, a galvanometer for deflecting the beam of light in accordance with sounds to be recorded, a slit, means for focusing said beam on said slit to form an image of said aperture and means for focusing the light passing through the slit on a film, the said aperture plate being provided with opposed triangular apertures having their vertices extended a distance not less than the altitude of the triangle, the said extension having sufficient width to prevent fogging in of the corresponding clear portion of the positive print.

EDWARD W. KELLOGG.
